[57] CLAIM

The ornamental design for a parts washer, as shown.

DESCRIPTION

FIG. 1 is an isometric view of a parts washer showing our new design;

FIG. 2 is a front elevation view thereof;

FIG. 3 is a rear elevation view thereof;

FIG. 4 is a left-side elevation thereof;

FIG. 5 is a right-side elevation thereof;

FIG. 6 is a bottom plan view thereof; and,

FIG. 7 is a top plan view thereof.

The details shown in broken lines in FIGS. 2 and 3 are shown for illustrative purposes only and form no part of the claimed design.
